ELBRIDGE W. STEVENS, OF BALTIMORE, MARYLAND.

GAS-MAKING AND CHARGE-FORMING APPARATUS FOR INTERNAL-COMBUSTION ENGINES.

1,048,224.

Specification of Letters Patent.

Patented Dec. 24, 1912.

Application filed July 8, 1910. Serial No. 570,938.

To all whom it may concern:

Be it known that I, ELBRIDGE W. STEVENS, a citizen of the United States, residing at Baltimore city, in the State of Maryland, have invented certain new and useful Improvements in Gas-Making and Charge-Forming Apparatus for Internal-Combustion Engines, of which the following is a specification.

10 My invention relates to gas making and charge forming apparatus for internal combustion engines designed more especially for utilizing the heavy oils for the purpose, instead of gasoline.

15 The operation of internal combustion engines with heavy oils has attained but a very limited measure of success, owing to the difficulty of forming explosive charges which will burn to perfect combustion without fouling the engine with deposits of carbon. At the same time an engine which can successfully operate on these oils is a great desideratum owing to the lower cost of the oil and the freedom from the dangers of explosion.

20 The object of my invention is to overcome the difficulties heretofore encountered in this field and to produce a reliable, effective, and economical engine of this type.

25 My gas making and charge forming apparatus utilizes the suction stroke of the piston to draw a mixture of oil and air, or oil, air and water, through the pores of a refractory porous fixing medium constructed and arranged in a novel way and utilizing the hot exhaust gases of the engine to heat said fixing medium to effect the homogeneous and stable union of the air and hydrocarbon while passing through the porous 30 medium and in such proportions and chemical constitution as to make a properly balanced explosive charge. The engine proper comprehends a cylinder with piston and intake valve connected to a new form of

40 gas making apparatus containing a refractory fixing cylinder of porous earthenware, a mixing valve for air and hydrocarbon leading into the said apparatus and a conduit from the exhaust of the engine to the 45 gas making apparatus whereby the porous cylinder is heated by the exhaust gases and is made to effect a union between the air and hydrocarbon as they are drawn through said hot, porous, refractory fixing cylinder, as

hereinafter more fully described with reference to the drawing in which:

Figure 1 is a sectional side elevation of the entire organization of coacting elements. Fig. 2 is a transverse section through line 2—2 of the gas making apparatus of Fig. 1. Fig. 3 is a similar section through line 3—3. Fig. 4 is a longitudinal section showing a modification of the fixing cylinder of the gas making apparatus and Fig. 5 is a modified form of the mixing valve adapted to mix hydrocarbon, air and water when introduced into the gas making apparatus.

In the drawing 1 represents any type of internal combustion engine having a cylinder 2, piston 3, intake valve 4, communicating with gas supply pipe 6, and exhaust valve 5 communicating with discharge pipe 7.

M is a cylindrical casing closed by two heads N and L. Concentrically within the same is supported a cylinder Y of a refractory porous nature, such as baked and unglazed earthenware made by mixing clay and carbon and removing the carbon by prolonged burning, which leaves the clay porous. Outside of the porous earthen cylinder is a cast iron cylinder D and inside of the porous cylinder is a cast iron cylinder G. Each of these iron cylinders is cast with a helical channelway, the outer cylinder D having interior helical channelway E, E¹, E², E³, E⁴, E⁵, and the inner cylinder G having exterior helical channelway F, F¹, F², F³, F⁴, F⁵, and these channelways are so spaced in relation to each other as to come directly opposite to each other with the porous cylinder wall between them forming an outer continuous helical channelway and an inner continuous helical channelway, so that gases can pass from the outer channelway to the inner channelway at a multiplicity of points throughout the porous cylinder. At intervening points, as at C C', the metal of the two iron cylinders abuts close against and in contact with the porous cylinder.

The interior helical channelway at F⁵ communicates with the supply pipe 6 that leads the explosive charge to the intake valve 4 of the engine and at its other end F¹ it is entirely closed except through the substance of porous cylinder Y. The outer helical channelway at E communicates at

the other end of the cylinder with a mixing valve H. This latter may be any kind of a mixing valve for mixing the hydrocarbon and air in proper proportion. The valve H shown, is what is known as the Lukenheimer valve, in which air is taken in at a and oil through a needle valve at c whose inlet ori-
5 fice is also covered and controlled by the beveled face of the spring seated intake valve b. The other end E⁵ of the channel-
10 way is entirely closed except through the substance of the porous cylinder Y.

The inner iron channeled cylinder G is supported concentrically from the heads N
15 and L by lag screws X X and the porous earthen cylinder Y and outer iron channeled cylinder D are concentrically supported upon the inner cylinder G. There is an open space inside the inner cylinder and outside
20 the outer cylinder and between the head L and the gas fixing cylinder and this open space is connected to the discharge pipe 7 of the exhaust valve of the engine so that all
25 three of the cylinders D, G, Y are surrounded by the hot gases of the exhaust which, after passing through the casing M, escape through an outlet at K. Both of the im-
pervious cylinders D and G are shorter than the outer casing cylinder M and wholly
30 within its head and at one end said cylinders D and G are off set from the head L of the casing by a lug into which one of the screws X is entered so that the spaces around
35 the outer cylinder D and within the inner cylinder G are in open communication with each other.

The operation of my engine is as follows: The passage of air and hydrocarbon through the porous cylinder is energized by a differ-
40 entiation of pressure on opposite sides of the porous cylindrical septum. This in the present instance is effected by suction on the inner side of the cylinder. On the suction stroke of the engine a partial vacuum is
45 formed in the cylinder 2, pipe 6 and the interior helical channelway F⁵ to F and this through the porous cylinder walls makes a reduced pressure or partial vacuum in the outer channelway F⁵ to E. This suction
50 allows the intake valve b of the mixing valve H to open and take in air from a and a limited and regulated amount of oil at c causing the two to become mixed in proper proportion. This mixture passes
55 through the walls of the porous cylinder at a multiplicity of points along the helical channelway. As this mixture passes through, the molecules are brought into intimate union and a fixed gas is formed by
60 the heat of the exhaust gases from the engine. It will be seen that at points C C' where the iron cylinders touch the porous cylinder, the hot exhaust gases heat the parts C C' which are made to directly transfer
65 their heat by conductive contact to the po-

rous cylinder so that the temperature of the porous cylinder at points between the outer and inner channelway is raised high enough to fix the finely mixed air and gas into a permanent stable gas that does not condense 70 nor deposit carbon. This fixed gas, it will be seen, constantly oozes through the walls of the porous cylinder into the inner channelway F to F⁵, so that the intake pipe 6 of the engine constantly supplies a high grade 75 of noncondensing gas to the engine from low grade oils not heretofore successfully employed. The admixture of air is very im-
portant as it supplies the oxygen to combine with the excess of carbon. The special form 80 of gasifying device, with a heating space inside the cylinder G and also outside the cylinder D, is correlated to a mixing valve mounted on the casing and mixing a heavy oil and air, in that such heavy oil not only 85 requires air in admixture, but a relatively high degree of heat for their gasification in a porous cylinder which is effectively supplied by the inner and outer application of heat to the porous cylinder. As the exhaust 90 passes into the casing M of the gas making apparatus it will be seen that the latter acts as a muffler and the heat units, which are ordinarily wasted, are converted into useful effect in heating the porous cylinder and 95 effecting the union between the hydrocarbon and air to make a fixed gas, which is due partly to the high temperature and partly to the minute subdivision and surface action of the refractory porous material as the two 100 bodies, air and vapor, pass through the porous cylinder. It will be seen that in the forced passage of air and gas through the porous cylinder the direction of passage is from the exterior to the interior, which 105 utilizes the principle of the arch in the cylinder to prevent breaking strains and the inner cylinder G holds and braces it at a plurality of points along its length against such stress.

In Figs. 1, 2 and 3 I have shown a straight plain porous cylinder and have formed the helical channelways in the two metal cylinders, but I may, as a modification, form the passageways in the porous cylinder and 115 use a straight and plain inner and outer metal cylinder as seen in Fig. 4, in which Y¹ is the porous cylinder, D¹ the outer metal cylinder and G¹ the inner metal cylinder. In this modification the transit of the gases 120 through the porous cylinder is parallel to the axis of the cylinders as indicated by the arrows.

As so far described my invention contem-
125 plates the union of air alone with the hydro-
carbon oil. I may, however, combine with the air and hydrocarbon a certain proportion of water in the form of vapor or steam. For this purpose a double mixing valve, as seen in Fig. 5, may be employed in which oil 130

and water are both brought into admixture with the air, or two mixing valves may be employed, one for oil and air and the other for water and air. Although designed 5 mainly for the utilization of the heavier oils, I would have it understood that I propose to use it with all grades of hydrocarbons and may vary the construction and arrangement in many respects without departing 10 from my invention as set forth in the claims.

As a means for starting the gas making apparatus before the engine comes into action, I provide the casing M, see Fig. 1, with two or more capped openings A A at the bottom 15 and two similar capped vents B B at the top. Through the openings A the flame of a gasoline torch is applied to preliminarily heat up the gas making apparatus, the products of combustion escaping through the 20 top vents B. As soon as the porous cylinder is sufficiently heated the starting torches are removed, the closing caps applied at A and B and the engine is started to suck the air and hydrocarbon through.

25 I claim,

1. A gas making apparatus, comprising a porous cylinder having passageways around it for the transmission of air and hydrocarbon through it at a plurality of points, 30 said passageways having inlet and outlet openings one of which is adapted to be connected with means for energizing the passage of air and hydrocarbon through the porous cylinder, and means for heating the 35 same.

2. A gas making apparatus, comprising a porous cylinder having passageways around it for the transmission of air and hydrocarbon through it at a plurality of points, 40 said passageways having inlet and outlet openings one of which is adapted to be connected with means for energizing the passage of air and hydrocarbon through the porous cylinder, and means for heating the 45 same consisting of an inclosing casing having an opening adapted to receive hot gases.

3. A gas making apparatus, comprising a porous cylinder having passageways around it for the transmission of air and hydrocarbon through it at a plurality of points, 50 said passageways having inlet and outlet openings one of which is adapted to be connected with means for energizing the passage of air and hydrocarbon through the porous cylinder, and means for heating the same consisting of a cylindrical casing having an opening in its end adapted to receive hot gases and also openings in the sides for initial heating.

60 4. A gas making apparatus, comprising a porous cylinder having continuous helical passageways around it for the transmission of air and hydrocarbon through it at a plurality of points said passageways having inlet and outlet openings one of which is

adapted to connect with means for energizing the passage of air and hydrocarbon through the porous cylinder, and means for heating the same.

5. A gas making apparatus, comprising a 70 porous cylinder having passageways around it for the transmission of air and hydrocarbon through it at a plurality of points, said passageways having inlet and outlet openings one of which is adapted to connect 75 with means for energizing the passage of air and hydrocarbon through the porous cylinder and said passageways being formed of grooved castings one inside and the other outside the walls of the porous cylinder and 80 abutting at intervals against said walls, and means for heating the same.

6. A gas making apparatus, comprising a porous cylinder having a passageway around its exterior surface and a passageway inside 85 said cylinder, an air and hydrocarbon mixing valve communicating with one of said passageways to pass the mixture of air and hydrocarbon through the same and one of said passageways having an outlet adapted 90 to connect with means for energizing the passage of air and hydrocarbon through the porous cylinder, an inclosing casing and means for passing hot gases into the casing and around and within the cylinder. 95

7. A gas making apparatus, comprising a porous cylinder having a helical passageway around its exterior surface and a helical passageway inside said cylinder, an air and hydrocarbon mixing valve communicating with one of said passageways to pass the mixture of air and hydrocarbon through the same and one of said passageways having an outlet adapted to connect with means for energizing the passage of air and hydrocarbon through the porous cylinder, an inclosing casing and means for passing hot gases into the casing and around and within the cylinder. 100

8. A gas making apparatus, comprising a 110 porous cylinder having a helical passageway around its exterior surface and a separate helical passageway around its interior surface, said passageways having an inlet and outlet, one of which is adapted to connect 115 with means for energizing the passage of air and hydrocarbon through the porous cylinder, an inclosing casing and means for passing hot gases into the casing and around and within the cylinder. 120

9. A gas making apparatus comprising, a tube of porous material, other tubes of substantially impervious material arranged one inside of said porous tube and the other outside thereof, there being a space between each of said latter tubes and the adjacent surface of the porous tube, means for delivering a hydrocarbon fluid to one of said spaces, there being a discharge duct leading from the other of said spaces, the inner im- 125 130

pervious tube having also a heating space within the same, a casing wholly inclosing all of said tubes and made of greater length than the same and off set from the sides of the tubes and also from one end of said tubes to form heating spaces for the reception of a heating fluid outside of the outer impervious tube, inside the inner impervious tube and between the ends of the impervious tubes 10 and the end of the casing.

10. A device for gasifying hydrocarbon liquids, comprising a tube of porous material, other tubes of substantially impervious material arranged the one inside of said porous tube and the other outside thereof, there being a space between each of said latter tubes and the adjacent surface of the porous tube, a mixing valve for mixing air and hydrocarbon and delivering the mixture 15 to one of said spaces, there being a discharge duct leading from the other of said spaces and means for circulating a heating fluid in heating proximity to said tubes.

11. A device for gasifying hydrocarbon liquids, comprising a tube of porous material, other tubes of substantially impervious material arranged the one inside of said porous tube and the other outside thereof, there being a space between each of said 20 latter tubes and the adjacent surface of the porous tube, a mixing valve for mixing air and hydrocarbon and delivering the mixture to one of said spaces, there being a discharge duct leading from the other of said spaces and means for circulating a heating fluid in heating proximity to said tubes. 25

12. A device for making an explosive gas 30 from hydrocarbon oils, comprising a tube of porous material, other tubes of substantially

impervious material arranged, the one inside of said porous tube and the other outside thereof, there being a space between each of said latter tubes and the adjacent surface 45 of the porous tube, a surrounding casing spaced away from said tubes, a mixing valve mounted on said casing for mixing air and hydrocarbon and delivering the mixture directly to one of said spaces beside the porous tube, there being a discharge duct leading from the other of such spaces, said casing having an inlet and outlet for circulating a heating fluid through the same. 50

13. A device for making an explosive gas 55 from hydrocarbon oils, comprising a tube of porous material, other tubes of substantially impervious material arranged, the one inside of said porous tube and the other outside thereof, there being a space between 60 each of said latter tubes and the adjacent surface of the porous tube, a surrounding casing spaced away from said tubes, a mixing valve mounted on said casing for mixing air and hydrocarbon and delivering the mixture directly to one of said spaces beside the porous tube, there being a discharge duct leading from the other of such spaces, said casing having an inlet and outlet for circulating a heating fluid through the same. 65

and the inner one of said impervious tubes having an opening through its center in open communication with the space between the casing and the outer impervious tube to receive the heating fluid on both sides of 70 the porous cylinder. 75

In testimony whereof I affix my signature in presence of two witnesses.
